UNITED STATES PATENT OFFICE.

WARREN C. WILLIAMS, OF TOLEDO, OHIO, ASSIGNOR OF ONE-HALF TO
FRANK C. SHERMAN, OF SAME PLACE.

DISH-CLEANER.

SPECIFICATION forming part of Letters Patent No. 628,292, dated July 4, 1899.

Application filed December 31, 1897. Serial No. 665,156. (No model.)

To all whom it may concern:

Be it known that I, WARREN C. WILLIAMS, a citizen of the United States, residing at Toledo, Lucas county, Ohio, have invented certain new and useful Improvements in Interchangeable Dish and Bottle Washing Machines, of which the following is a specification.

My invention relates to and its object is to provide a machine which may be utilized interchangeably as a dish-washing machine and as a bottle-washing machine. I attain these objects by means of the devices, mechanism, and arrangement of parts hereinafter described, and shown and illustrated in the accompanying drawings, made part hereof, in which—

Figure 1 is a vertical sectional elevation of my device, taken on line $x-x$, Fig. 2; Fig. 2, a top plan view with portions of the lid broken away; Fig. 3, a vertical sectional elevation taken on line $y-y$, Fig. 2; and Fig. 4, a side view, partly in section, showing my device adapted as a bottle-washer.

Like numerals of reference indicate like parts throughout the drawings.

In the drawings, 1 is a rectangular vessel, of sheet metal, supported on legs 2 and having a closely-fitting rectangular lid 3. One of the vertical sides of the vessel is curved outwardly, as at 4, forming, approximately, a semicylindrical recess off the chamber of the machine. The bottom of the vessel is provided with a depression 5, coinciding with the bottom of the recess 4. This depression gradually tapers away from the bottom of recess 4, or, if preferred, the whole bottom of the vessel may be inclined uniformly. Within the vertical semicylindrical chamber 4 is vertically disposed a pump-cylinder 6, which is removably secured in position by means of cleats 7 engaging buttons or hooks 8 upon the inner wall of the vessel. The bottom of the pump-cylinder projects below the general level of the bottom of the vessel into the sunken portion formed by the meeting of the recess 4 and the depression 5. In the pump-cylinder is a plunger 9, (indicated by dotted lines in Fig. 1,) having a pump-rod 10 engaging a horizontal handle 11, pivoted upon an upright bracket 12, riveted to a wall of

the machine. In the bottom of the pump-cylinder is a lift-valve 13.

From the interior of the pump-cylinder, just above the valve, leads vertical pipe 14 to a point above the level of the top of the lid. The diameters of the pump-cylinder 6 and of the vertical tube 14 permit the two to be placed side by side within the semicylindrical diameter 4, so that they do not protrude into the rectangular chamber of the vessel. From the top of the tube 14 leads tube 14^a, extending above the top of the lid to a point just above the center of the lid and thence downwardly through the lid into the chamber of the machine. The connection between the tubes 14 and 14^a is an elbow 14^b, loose upon the two sections of pipe to which it is connected. At the other extremity of the tube 14^a is another elbow 14^c, forming a slip-joint, so that the mouth of the tube may be turned either downwardly or upwardly. It will be seen that by this arrangement of elbows and slip-joints the horizontal portion 14^a may be disengaged or may be swung horizontally and that the vertical portion at the extremity of the horizontal pipe 14^a may be disengaged or may be swung, as desired, in a vertical plane.

Secured to the under side of the lid is a wheel 15, having its vertical shaft 16 arranged axially of the mouth of the discharge-pipe. This shaft is journaled and stepped at bottom in a stout wire frame 17, secured to the bottom of the lid, and at top in a wire loop or cross-piece 18 in the discharge-pipe. The wheel 15 is made up of a series of radial curved blades or vanes, somewhat after the fashion of a propeller, as fully appears from Figs. 2 and 3. Disposed horizontally on the bottom of the dish-chamber of the machine is a wire rack R, designed to support the dishes and to admit of their rapid drainage.

The operation of my device thus far described is as follows: Assuming that the parts are assembled as above described and as illustrated in the drawings, the lid is removed, the interior of the vessel is filled with soiled dishes to be washed, a proper amount of boiling or very hot water is poured into the vessel, the rectangular lid is placed in position, the elbows 14^b and 14^c are slipped vertically into place, and the pump-handle is now operated.

Water is now drawn into the pump-cylinder through the valve 13 and is forced out through pipes 14 and 14^a downwardly onto the curved blades of the wheel 15. The force of the stream causes this wheel to revolve rapidly and to throw the water violently in every direction, by means of which the dishes are cleansed. The dish-water is now drawn off through plug 19, near the bottom of the sump, the dishes are allowed to drain a short time, hot rinsing-water is supplied to the machine, the pumping is repeated, and the dishes are now thoroughly cleansed and the operation is complete.

20 20 is a tube which is adapted at one end to slip upon and fit the discharge end of the elbow 14^c and is at its other end contracted and perforated. Between the large end of this tube and the perforations are projecting fingers 21. Now if the lid 3 be removed the elbow 14^c turned with its mouth upwardly, the large end of the pipe 20 slipped over the upturned mouth of the elbow, and if an inverted bottle be slipped over the perforated 25 extremity of the tube 20 and allowed to rest

upon the fingers 21 several strong minute streams of water will be discharged into the bottle, thoroughly cleansing the same, the water escaping from the mouth of the bottle and dripping into the open chamber below.

Having described my invention, what I claim, and desire to secure by Letters Patent, is—

In an interchangeable dish and bottle washing machine, a vessel, a pump adapted and arranged to take water from the bottom of the chamber of said vessel, a discharge-pipe leading from said pump to the top of said chamber, a slip-joint elbow at the top of said pipe, a horizontal pipe leading from said slip-elbow, another slip-joint elbow at the opposite end of said horizontal pipe, whereby said horizontal pipe may be swung in a horizontal plane, and whereby the discharge extremity of said latter slip-joint elbow may be swung in a vertical plane.

WARREN C. WILLIAMS.

In presence of—
T. J. DOWLING,
L. E. BROWN.
